DESIGN FOR A HAIRPIN HOLDER

Lessie Hammonds, Fort Worth, Tex.

Application October 8, 1938, Serial No. 80,333

Term of patent 3½ years

To all whom it may concern:

Be it known that I, Lessie Hammonds, a citizen of the United States, residing at Fort Worth, in the county of Tarrant and State of Texas, have invented a new, original, and ornamental Design for Hairpin Holders, of which the following is a specification, reference being had to the accompanying drawing, forming part thereof.

I claim:

The ornamental design for a hairpin holder, substantially as shown.

LESSIE HAMMONDS.
